EYE EXERCISER

Gordon P. Felts and Robert W. Seeger,
Pasadena, Calif.

Application December 3, 1949, Serial No. 131,005

1 Claim. (Cl. 128—25)

1

Our invention relates to improved means and method for exercising the muscles of the eyes to strengthen eye sight and correct vision.

Among the objects of the present invention is to prevent liquid which is used for applying pressure and treatment of the eyeballs from leaking out of a mask which is used to apply the liquid. A further object is to provide an improved method by which the eyeballs are strengthened and vision is corrected. In the present invention fluid of predetermined or variable pressure and kind is applied either while dormant or while circulated in contact with the eyeballs for a predetermined period during which the eyes of a patient are exercised. We have found in practice that it is difficult to apply a mask which is used on the face and over the eyes of a patient so as to prevent fluid which is employed in contact with the eyeballs under varying conditions of pressure from leaking and reducing in pressure. Leaking of exercising fluid therefore reduces the effectiveness both of the apparatus and method employed and this objection is also corrected by our invention. It also has been found that any leaking of fluid from the mask on the face of the patient is annoying and therefore objectionable. Among the objects of the present improvement is to provide an improved method and means for overcoming the above objections and for applying fluid medium under constant or variable pressure or while dormant or circulating in contact with the eyeballs and for sealing a mask which is employed tightly on the face surrounding the eyes so as to prevent exercising fluid within the mask from losing pressure and leaking. A further object is to fasten and seal the mask which is employed over the eyes and on the face of a patient who is treated while the eyes of the patient are exercised simultaneously under the direction of an attendant and during contact with exercising fluid.

In the accompanying drawings forming part of this specification, Fig. 1 is an elevation looking into the back of our improved mask by which our improved method of treating the eyeballs is carried into practice, part of the strap by which the mask is first held on the face, being broken away; Fig. 2 is a bottom plan looking down on the lower edge of the mask; Fig. 3 is a section of a detail taken approximately on the line 3—3 of Fig. 1; Fig. 4 is a section taken on the line 4—4 of Fig. 1; Fig. 5 is another section of a portion of the structure taken approximately on the line 4—4 of Fig. 1, at increased scale; Fig. 6 is a typical illustration showing our improved mask connected with a type of liquid source for exer-

2

cising the eyes, and with a source of negative air pressure for simultaneously holding the mask firmly and tightly on the face of a patient; Fig. 7 is a side elevation illustrating an alternative construction by which exercising liquid is adapted to be circulated continuously through the fluid chamber in the mask and in contact with the eyeballs of a patient; Fig. 8 is a side elevational section of an alternative construction of our invention, showing diagrammatically the mask applied on the face of a patient; Fig. 9 is a section of a detail taken approximately on the line 9—9 of Fig. 8; and Fig. 10 is a section of a detail showing another alternative construction of our invention.

The drawings represent our improved exerciser which employs a mask A. This mask is molded into a soft contained body out of rubber, cellophane or other suitable flexible material and has an inner concave surface 10 (Fig. 2), which is shaped so as to conform approximately with and fit the surface of that portion of the face over the eyes of a patient on whom the mask is applied. In practice the material out of which the mask is made may be opaque, transparent, or translucent, and may be relatively thin and flexible. The mask is of substantially universal shape and size so that a single mask will conform and fit faces of a number of persons. Usually the mask is first fastened in place on the face over the eyes by a strap 11, which is buckled around the head of the patient. The lower portion of the mask is suitably formed with a nose cavity 12, which is shaped so as to fit closely over the bridge of the nose. The body portion of the mask over the eyes is formed with an inner forwardly extended chamber 13, which latter is surrounded laterally by a relatively broad endless margin 14. The inner surface 10 of said margin, which is concave, conforms and fits the surface of the face including the bridge of the nose and has a circuitous suction groove 15, which extends entirely around the chamber 13, within the mask and includes the nose portion. The suction groove has an admission passage 16 leading outwardly through the margin 14, at any convenient location.

The suction groove holds a relatively thin, endless and flexible channel insert 17, the body portion of which is cemented or otherwise fastened in the endless and circuitous groove 15. Said insert conforms with the groove 15 throughout its length and is formed on its opposite edges with a pair of endless flexible suction flaps 18. These flaps may be recessed freely at 19 (Fig. 4), in the marginal wall 14 of the mask and are adapted to

function and bend outwardly by suctional force to produce fluid tight contact with the surface of the face and thus seal the mask when the latter is applied in use. The channel member 17 has an air suctional supply tubing 20 (Fig. 5), which is extended outwardly through a nipple 21 on the margin 14 and is connected with a suitable source of negative air or other fluid pressure. As shown in Fig. 6, the negative fluid pressure source is produced by means of the air siphon B, of usual construction, which is actuated and controlled by the pressure fluid supply faucet 22.

The circuitous channel insert 17 is composed of rubber, cellophane or other suitable freely flexible material, whereby the flaps 18 thereof are actuated by suction fluid. In this manner a fluid tight connection is produced between the endless margin 14 and the surface of the face of a patient on which the device is applied. By this means the mask is held and sealed tightly on the face to prevent leaking of exercising fluid from chamber 13 when in use.

The chamber 13 is provided with a fluid supply duct 23, which extends outwardly through the nipple 24 and is shown connected with a faucet D, which is adapted to control the supply of exercising fluid at any desired pressure and temperature for application to the eyeballs.

In use the mask is first fastened on the head over the eyes of a patient by the strap 11. While thus held in place the suction siphon B is operated to produce negative air pressure in the channel 17, whereupon the suction fluid flaps 18 are actuated and secured firmly and tightly by suction on the face over the eyes of the patient. The fluid chamber 13 is thus prevented from leaking. While the mask is thus held in place the eye exercising fluid which is controlled by an attendant at any predetermined constant or variable pressure and suitable temperature is applied through chamber 13 in contact with the eyeballs while the latter are exercised under the control of an attendant or operator to correct and strengthen eyesight and vision. In this manner the function of the device and the method of exercising the eyes and improving eye sight are made more effective.

In Fig. 7, the chamber 13 of the mask is provided with inlet and outlet ducts 25 and 26, through which the exercising fluid may be circulated in a continuous stream while maintained at any suitable pressure and temperature which best suits the condition of the eyeballs which are exercised.

In Fig. 8, the mask C is shown when extended below the nose and is suitably shaped with its margin 14 adapted to be tightly held by suitable flaps 18 upon the surface of the face of the patient. In this construction air tubes 27 and 28 (Figs. 8 and 9) are inserted tightly in the passages of the nose and extend outwardly through the wall of the mask. These tubes are adapted to

permit free breathing by the patient through the nose without any leaking of fluid from within the mask.

In Fig. 10, the means for sealing and securing the mask tightly on the face of a patient is provided by a pair of continuous flexible flaps 30-30, which are formed with a continuous suction channel 31 therebetween and as an integral part of the body of the mask on the inner surface throughout the length of the margin 14. The entire mask including the suction flaps 30-30, with the suction channel 31 between is molded integrally out of rubber or other suitable flexible material, whereby the mask can be held tightly on the face of a patient by suction applied through the channel 31 and by the flaps. A dust 32 is connected with the channel 31 by which a source of fluid suction pressure is connected with the channel 31. By this construction the mask and sealing flaps are a self contained unit which simplifies construction and improves the effectiveness of the device.

Further modifications are contemplated within the spirit of the invention and the scope of the following claim.

We claim:

An apparatus for exercising muscles controlling the movement of the eyeballs, comprising a flexible mask shaped to fit closely over the face of the patient and having therein a single, unitary, fluid-holding chamber elliptical in shape and covering an extensive area of the face defined by the middle forehead, nose bridge and the outer extremities of the eye sockets, an endless groove seated in the inner surface of said mask and defined by the periphery of the aforesaid elliptical fluid-holding chamber, a pair of inner and outer endless suction-actuated flaps extending from said endless groove to form an air exhaust passage therebetween and disconnected from said fluid-holding chamber, a source of suction fluid connected with said exhaust passage for causing said flaps to adhere tightly to the face of the patient and positively prevent fluid from leaking from within said chamber and over the face of the patient, and a separate source of fluid under pressure connected with said chamber for exerting pressure on the eyeballs.
